SEALED PACKAGE.

Application filed November 22, 1924. Serial No. 751,654.

This invention relates to packaging and particularly to a side seal and package. It is especially applicable in the packing of foodstuffs and the like in packers' jars or tumblers.

Heretofore in the art packages have been formed by side sealing a closure to a tumbler or the like. The side seals have been formed in various ways and packages have been produced which are satisfactory for some purposes. However the prior art seals which are commercially desirable from the standpoint of economy of material and labor, sometimes yield under the action of substantial pressures developed within the package. When packages of foodstuffs are heat treated to process the contents, substantial internal pressures are usually developed; and hence these prior art packages can be heat treated only with fairly elaborate equipment and by the exercise of considerable care to maintain the packages under a sufficient external pressure which is substantially equal to the internal pressure developed.

The failure of the prior art seals under the action of internal pressure is usually due to one or more of the following characteristics of those seals: (1) gasket not held tightly against the sealing wall of the vessel; (2) gasket not so held against the sealing wall that there is firm pressure throughout a wide zone of contact with the sealing wall; (3) lower edge of the gasket not adequately supported, thereby permitting the gasket to be crowded downward by the pressure within the vessel; (4) gasket retained in a bead which is so shaped when the seal has been completed that there are crevices, which in actual practice the gasket often fails to fill at the time the seal is made. Under the action of the internal pressure developed by heat treatment of the package the gasket may recede into the such crevices thereby impairing the seal.

The principal object of the present invention is to provide a package with an economical seal which is capable of withstanding a high pressure developed within the package.

Another object of the invention is to provide a package capable of being side sealed

with a chuck or die and capable of withstanding a high internal pressure.

An important object of the invention is to provide a side sealed package which requires a minimum amount of metal in the closure to locate the seal a given distance below the mouth of the vessel closed.

A further object of the invention is to provide a side seal in which a metal pressure band holding a gasket against a sealing wall is held in place by a metal retaining ring.

A still further object of the invention is to provide a side sealed package in which the seal is effected by a gasket which is well supported and held firmly against a sealing wall.

Other objects will be apparent from the description of the invention.

In accordance with the above and other objects of the invention the difficulties of the prior art are overcome by a package which is illustrated as comprising a packer's tumbler sealed by means of a gasket and a sheet metal closure. The closure comprises a cover portion which rests on top of the tumbler and a cylindrical portion which depends from the periphery of the cover portion and embraces the vessel through a zone contiguous to its mouth. An annular shelf extends substantially horizontally outward from the bottom of the cylindrical portion, and a gasket is positioned immediately below the shelf so as to be against a sealing wall of the vessel and have its upper edge in contact with the horizontal shelf. A band of metal depends from the periphery of the shelf and this band is deformed so as to be somewhat concaved and slope downwardly and inwardly thereby forming a pressure band which urges the gasket throughout its entire width directly against the sealing wall of the vessel. In order to hold the lower or free edge of the pressure band in its restricted condition there is provided an inverted horizontal flange which is reduced in diameter when the seal is made and forms a retaining ring which holds the pressure band against outward movement. This flange also supports the lower edge of the gasket, thereby preventing it from being pushed or distorted downwardly by pressure developed with the package. The finish of

the vessel may be provided with a small bead preferably near the upper limit of the sealing zone to engage the gasket and thereby greatly increase the limit of internal pressure which the seal will withstand.

Figure 1 of the drawings is an elevation of a package embodying the present invention.

Figure 2 is an enlarged fragmentary sectional view showing the closure before sealing and one means for making the seal.

Figure 3 is an enlarged fragmentary sectional view showing the deformation of the closure bead by the sealing operation.

Figure 4 is an enlarged fragmentary sectional view showing the completed seal.

Figure 5 is an enlarged fragmentary sectional view showing an alternative form of the seal.

Referring to the drawings, which illustrate a preferred form of the invention, a packer's jar or tumbler 1 is provided with a closure comprising a cover portion 2 from which depends a cylindrical portion 3 which 25 embraces the tumbler through a zone contiguous to its mouth. Extending substantially horizontally outwardly from the lower edge of the portion 3 is an annular shelf 4. After the closure has been applied, but before the seal has been made, a cylindrical metal band 5 depends from the periphery of the shelf 4 and at the bottom of the band is an inturned horizontal flange 6 which supports a rectangular gasket 7 adjacent to the sealing wall of the tumbler 1, as shown in Fig. 2. By suitable means such as a chuck or reducing die shown in Fig. 2 the depending cylindrical portion is deformed inwardly toward the sealing wall forming a metal 35 pressure band which is somewhat concaved and slopes inwardly and downwardly from the periphery of the shelf 4, as shown in Fig. 3. The reducing die decreases the diameter of the ring or flange 6, and thus this 40 flange becomes a retaining ring which holds the pressure band 5 constricted. Outward movement of the bottom of the pressure band being prevented, this band exerts a firm pressure upon the gasket 7 holding it 45 directly and tightly against the sealing wall throughout the entire width of the gasket, as shown in Fig. 4. The upper edge of the gasket is in contact with the shelf 4 and the lower edge is supported by the 50 horizontal flange 6, and thus the gasket is supported on all sides insuring its maintenance under compression. It is seen that the cap bead formed by the portions 4, 5, and 6 is free from crevices and hence there 55 is no danger of the gasket failing to completely fill the bead when the seal is made. Furthermore the lower edge of the gasket is well supported since the lower corner lies in the right angle formed by the flange 6 and the lower portion of the pressure band 60

5, and hence it is impossible for the gasket to in any way recede or to crawl downward under the influence of force applied to the top of the gasket by pressure developed within the container.

The seal as shown in Fig. 4 is capable of withstanding a considerable internal pressure and hence when the package is heat treated it is not necessary to exercise particular care to maintain it under an external pressure which is accurately equal to the internal pressure developed by the contents of the package. In the form of seal shown in Fig. 5, the finish of the vessel 75 1 is provided with a bead 8 which projects into the gasket 7 preferably near the top of the gasket. The gasket being held firmly under compression, this bead so greatly increases the internal pressure required to blow off the closure that the package may be heat treated to process the contents without placing it under an external pressure.

In the less expensive grades of packers' tumblers the process of manufacture is such that many of the pieces have irregularities close to the mouth. For this reason it is desirable to place a side seal at a distance below the mouth of the tumbler. With applicant's seal the shelf 4 is not curved or projected upward by the sealing operation 90 and thus the gasket is not drawn toward the mouth while the seal is being made. For this reason applicant's closure requires a minimum amount of metal to place the seal a given distance below the mouth of the tumbler.

It is realized that the present invention may be utilized in forms other than particularly disclosed and hence it is desired that the foregoing disclosure be considered as illustrative and not in the limiting sense.

Having thus described my invention, what I claim:—

1. A sealed package comprising a vessel having a sealing wall adjacent its mouth; in combination with closure means comprising a normally rectangular gasket in contact with said sealing wall; a substantially horizontal annular shelf in contact with the upper surface of the gasket; and a deformed band of metal depending from said shelf and holding said gasket directly against said sealing wall, said band of metal before deformation being in the form of a cylinder attached to the periphery of said shelf and having a substantially horizontal inturned flange at its lower edge and the band after deformation sloping downwardly and inwardly from the periphery of said shelf with the inturned flange substantially horizontal and supporting the lower edge of said gasket.

2. A sealed package comprising a vessel having a sealing wall adjacent its mouth; in combination with closure means comprising

ing a cover portion; a cylindrical portion depending from said cover portion and embracing said vessel; a gasket in contact with said sealing wall; an annular shelf extending substantially horizontally from the lower edge of said cylindrical portion, said shelf being in contact with the upper surface of said gasket; and a deformed band of metal depending from said shelf and holding said gasket directly against said sealing wall, said band of metal before deformation being in the form of a cylinder attached to the periphery of said shelf and having a substantially horizontal inturned flange at its lower edge, and the band after deformation sloping downwardly and inwardly from the periphery of said shelf with the inturned flange substantially horizontal and supporting the lower edge of 20 said gasket.

3. A sealed package comprising a vessel having a substantially cylindrical sealing wall adjacent its mouth and a bead formed on said sealing wall; in combination with 25 closure means comprising a normally rectangular gasket in contact with said sealing wall and said bead, a substantially horizontal annular shelf in contact with the upper surface of the gasket, a band of metal depending from said shelf and deformed inwardly to urge said gasket directly against said sealing wall throughout a wide zone of contact including said bead whereby a powerful seal is obtained, and a flange in-turned from the lower edge of said band to support the lower edge of the gasket, said flange being substantially horizontal after deformation of the band of metal.

4. A sealed package comprising a vessel 40 having a sealing wall adjacent its mouth; in combination with closure means comprising a gasket in contact with said sealing wall; a substantially horizontal annular shelf in contact with the upper surface of 45 said gasket; and a deformed band of metal depending from said shelf and holding said gasket directly against said sealing wall, said band of metal before deformation being in the form of a cylinder attached to the periphery of said shelf and having a substantially horizontal inturned flange at its lower edge, and the band after deformation being generally concave and sloping downwardly and inwardly from the periphery of 50 said shelf with the inturned flange substantially horizontal and supporting the lower edge of said gasket.

5. A sealed package comprising a vessel 55 having a sealing wall adjacent its mouth; in combination with closure means comprising a gasket in contact with said sealing wall; an annular shelf in contact with the upper surface of said gasket; a pressure band of deformed metal sloping downwardly and inwardly from said annular

shelf, said pressure band throughout a substantial portion of its height being substantially parallel to said sealing wall and holding said gasket directly against said sealing wall; and a retaining ring holding the lower 70 edge of said pressure band in constricted condition.

6. A sealed package comprising a vessel having a sealing wall adjacent its mouth; in combination with closure means comprising a gasket in contact with said sealing wall; an annular shelf in contact with the upper surface of said gasket; a pressure band of deformed metal sloping downwardly and inwardly from said annular 75 shelf, said pressure band having in its lower portion a zone of substantial height substantially parallel to said sealing wall and holding said gasket directly against said sealing wall; and a retaining ring holding 80 the lower edge of said pressure band in constricted condition, said retaining ring supporting the lower edge of said gasket.

7. A sealed package comprising a vessel having a sealing wall adjacent its mouth; in combination with closure means comprising a normally rectangular gasket in contact with said sealing wall; an annular metal portion in contact with the upper surface of said gasket, a pressure band urging said gasket against said sealing wall, said band being deformed toward said sealing wall and having in its lower portion a zone of substantial height substantially parallel to said sealing wall; and an inturned flange at the lower edge of said pressure band and forming therewith an angle which receives the outer lower corner of the gasket and supports the same, said flange being narrow and leaving a large portion of the edge 95 of the gasket exposed to facilitate opening of the package.

8. A sealed package comprising a vessel having a substantially cylindrical sealing wall adjacent its mouth and a bead formed on said sealing wall; in combination with closure means comprising a gasket in contact with said sealing wall and said bead, an outwardly extending annular metal portion in contact with the upper surface of the gasket, and a band of metal depending from said annular metal portion and deformed inwardly to urge said gasket directly against said vessel wall throughout a wide zone of contact including said bead, said band having in its lower portion a zone of substantial height substantially parallel 110 to said sealing wall.

9. A sealed package comprising a vessel having a substantially cylindrical sealing wall adjacent its mouth and a bead formed on said sealing wall, in combination with closure means comprising a gasket in contact with said sealing wall and said bead; an outwardly extending annular metal por- 125

tion extending above the upper surface of the gasket; a band of metal depending from said annular metal portion and deformed inwardly to urge said gasket directly against said vessel wall throughout a wide zone of contact; and an inturned flange at the lower edge of said band of metal.

10. A sealed package comprising a vessel having a side wall sealing surface in combination with closure means comprising a gas-

ket; an outwardly extending member in contact with the upper surface of said gasket; and a pressure band of deformed metal sloping downwardly and inwardly from said outwardly extending member; said pressure band throughout a substantial portion of its height being substantially parallel to said side wall and holding said gasket directly thereagainst. 15
